UNITED STATES PATENT OFFICE.

JOSEPH DAVIDSON, OF FORRESTVILLE, MARYLAND.

POCKET-BOOK.

SPECIFICATION forming part of Letters Patent No. 645,460, dated March 13, 1900.

Application filed June 9, 1899. Serial No. 719,946. (No model.)

To all whom it may concern:

Be it known that I, JOSEPH DAVIDSON, a subject of the Emperor of Russia, residing at Forrestville, in the county of Prince George 5 and State of Maryland, have invented certain new and useful Improvements in Pocket-Books; and I do hereby declare the following to be a full, clear, and exact description of the invention, such as will enable others skilled 10 in the art to which it appertains to make and use the same.

My invention relates to pocket-book fastenings; and the object is to provide a pocket-book with a fastening device which is unique, 15 novel, and useful; and the invention consists in the novel construction and combination of parts, as will be hereinafter fully described, and then particularly pointed out in the claim.

I have fully and clearly illustrated my invention in the accompanying drawings, 20 wherein—

Figure 1 is a front view in elevation of a pocket-book with my improvements applied thereto in locked condition. Fig. 2 is a vertical central transverse section through the pocket-book. Fig. 3 is a top plan view of a pocket-book with my improvements applied. Fig. 4 is a view of the two-part or flap pocket-book having my improvements applied.

Referring to the drawings, A designates a pocket-book of the bellows or extension variety provided with an overlapping flap 1, adapted to lie over and against the front of the book, as indicated in Figs. 1 and 2. In 30 the front plate *a* of the book is secured a screw-eye 2, the eye of which is adapted to be projected through a suitable opening 3, made in the flap 1 of the pocket-book, as indicated in Figs. 1 and 2 of the drawings. Secured to the 35 front plate *a* is a strap 4, in the free end of which is fastened a disk or medal 5, of any suitable design, or a ring may be substituted for the disk or medal. At the other end of the front plate or flap of the pocket-book is 40 secured another strap 6, substantially of the same length as the strap 4 and carrying on its free end a ring 7, which incloses the strap 4, as indicated in the drawings.

The inverted-V-shaped straps secured at 45 their lower ends to the outside of the pocket-book and extending above the pocket-book serve a twofold purpose—viz., that of sus-

pending the pocket-book from the wearer's waist and as a tie-band when the device is not worn. This is readily accomplished for the 55 reason that there are no surplus flaps attached to the pocket-book to interfere with the wrapping and tying.

B designates a bar, which constitutes the lock or fastener of the pocket-book and in locking condition and arrangement is slidingly and detachably projected through the eye 2. In the bar B are formed two inclined and longitudinally-arranged slots 8 9, the slot 8 being substantially twice the length of the slot 9 in 65 order that sufficient room or space may be afforded for the passage of the disk or ring 5 in the operation of unlocking the pocket-book, as hereinafter specified. The strap 4 is loosely passed through the slot 8, and the strap 6 is 70 loosely passed through the slot 9 of the bar B. I have shown it as consisting in contour of a miniature gun. The strap 6 is permanently retained in the slot 9; but in the manipulations of the parts in unlocking the pocket-book the strap 4, with the ring or disk on the 75 end, is passed through and free of the slot 8. It is obvious that in forming the slots in the bar one of the slots is somewhat longer than the other, for the reason that when the ring is 80 manipulated in passing the same over the end of the bar the lengthwise play in the longest slot permits the bar to move endwise, when the ring can be easily carried over the end of 85 said bar.

To unlock the pocket-book, the ring 7 is slipped down on the strap 4 until the bar B is reached, when the ring is carried outward and passed over the end of the bar and then moved back along the bar until sufficient slot-space 90 is provided for the passage of the ring or disk of strap 4. This ring or disk 5 is then passed through the slot 8, and then the ring 7 is moved outward over and free from the end of the bar, and then the bar may be pulled back free from the eye 2, and the flap is then free to be opened and the interior of the pocket-book accessible. To lock the pocket-book, the flap is turned into proper position with the eye projecting, and then the bar B is drawn back 95 and passed through the eye. The ring 7 is then brought down and passed over the end of the bar and drawn back thereon until slot-space for the disk is made. The disk 5 is then 100

passed up through the slot, and then the ring 7 is moved forward over and free from the end of the bar, and the book is locked.

It will be observed that the end wall of the 5 slots are inclined in the direction of the inclines of the straps when extended, thereby preserving the edges of the straps from abrasure and wear in ordinary use and also in manipulation of the straps in the process of opening the pocket-book. This construction also holds the bar against lateral movement when the straps are extended and the book is held in suspension.

Of course small chains may be substituted 15 for the straps, and any ornamentation desired may be placed on the exterior of the pocket-book.

In Fig. 4 I have illustrated the invention as applied to a bellows or accordion style of 20 pocket-book, wherein the opposite rims of the frame of the book are provided with coincident and alining eyes $a^x b$, through which the

bar B is passed, as indicated in the drawings. The manipulations in locking and unlocking in this style are identical with that of the single ring or eye fastening. 25

Having thus described my invention, what I claim, and desire to secure by Letters Patent, is—

The combination with the pocket-book and 30 straps having the ring and disk secured at their upper end of the bar constructed with the long and short slots to receive said straps the longer slot, adapted to give sufficient lengthwise play to the bar in manipulating 35 said bar and ring in fastening and unfastening the book, all arranged as herein shown and described.

In testimony whereof I affix my signature in presence of two witnesses.

JOSEPH DAVIDSON.
